UNITED STATES PATENT OFFICE.

SHERMAN H. PAXTON, OF ST. PAUL, MINNESOTA.

HAND MARKING OR PRINTING DEVICE.

1,364,301.

Specification of Letters Patent.

Patented Jan. 4, 1921.

Application filed September 10, 1919. Serial No. 322,811.

To all whom it may concern:

Be it known that I, SHERMAN H. PAXTON, a citizen of the United States, residing at St. Paul, Minnesota, have invented certain new and useful Improvements in Hand Marking or Printing Devices, of which the following is a specification.

This invention relates to improvements in hand marking or printing devices.

10 The main objects of this invention are:

First, to provide an improved marking device well adapted for the marking of packages or parcels having yielding and more or less uneven surfaces.

15 Second, to provide an improved marking device which may be conveniently and rapidly manipulated.

Third, to provide an improved hand marking device having a rotating printing roller which may be operated in either direction.

20 Fourth, to provide an improved hand marking device which produces clear imprints and may be operated a large number of times without replenishing the ink supply.

25 Fifth, to provide an improved hand marking device in which the operative parts are all incased so that they are protected from dust and kept sanitary and the hands of the operator are not likely to come into contact with the ink.

Sixth, to provide an improved marking device in which the parts are simple and economical to produce and assemble, various 30 parts being duplicates, thereby reducing the cost of manufacture.

Further objects, and objects relating to structural details, will definitely appear from the detailed description to follow.

35 I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a side view of a hand marking device embodying the features of my invention.

Fig. II is a side view thereof, with one of the end plates of the housing removed, the handle being broken away.

Fig. III is a detail view, mainly in vertical central section, on a line corresponding to line 3—3 of Figs. I and II.

Fig. IV is a detail section through the inking roller on a line corresponding to line 4—4 of Fig. III.

Fig. V is a detail section through the inking roller on a line corresponding to line 5—5 of Fig. III.

Fig. VI is an enlarged detail section on a line corresponding to line 6—6 of Fig. II, showing details of the inking rollers.

Fig. VII is a detail section on a line corresponding to line 7—7 of Fig. III, showing details of the inking roller actuating means.

In the drawing, similar reference characters refer to similar parts throughout the several views, and the sectional views are taken looking in the direction of the little arrows at the ends of the section lines.

Referring to the drawing, I provide a housing consisting of a central body portion 1 and detachable side plates 2. The side plates are duplicates. The parts may be conveniently made as die casting. The body member 1 is shell-like and provided with lugs 3 adapted to receive the side plate attaching screws 4. At its lower end the body member has an opening at 5. At its upper end it has a threaded extension 6 adapted to receive the handle 7. The side plates 2 have opposed bosses 8 toward their upper ends adapted to receive the shaft 9 for the ink supplying roller 10 carrying the inking pad 11. The ink may be supplied to this pad, as required, by removing the handle 7.

At their lower ends the side plates 2 are provided with opposed bosses 12 into which the printing roller stub spindles 13 are threaded. Between the bosses 8 and 12 the side plates have horizontal offsets providing horizontal internal channels 14.

The printing roller 15 is mounted on the inner ends of the spindles 13, which have thrust collars 16 supporting the printing roller longitudinally. On the outer sides of these thrust collars are driving members 17, having driving lugs 18 coacting with the internal driving lugs 19 of the printing roller, the lugs 18 of the driving members being disposed on opposite sides of the driving lugs 19 of the printing roller, as is clearly shown in Figs. IV and V.

The driving members 17 are actuated by the coiled springs 20, which are arranged within the barrels 21 provided therefor on the side members, the barrels being concentric with the bosses 12. The outer ends of

these springs are engaged through slots 22, see Fig. VII, while their inner ends are engaged with notches 23 in the driving members, see Figs. IV and V. Thus arranged, 5 the springs act oppositely to return the printing roller to its initial position, one spring acting to return it when the roller is rotated in one direction, and the other acting to return it when it is rotated in the 10 opposite direction.

The roller has recesses 24 in its ends which receive the mechanism described, thereby permitting a compact arrangement of the parts. With the parts thus arranged, the 15 roller is yieldingly held in its initial position and may be actuated in either direction by placing it upon the surface to receive the imprint and moving thereon in either direction. As soon as raised from the 20 surface, one or the other of the springs will return the roller to its initial position.

The type shown conventionally at 25 is preferably formed of rubber and I preferably form the resilient annular tread 25 members 26 integral therewith. These resilient tread members 26 are disposed at the ends of the printing roller and serve to support it during its rotation across blank spaces in the type, and also prevent the type 30 being pressed down to such an extent as would produce blurred and irregular imprints. The type is shown as molded integral, but it will be understood that type 35 may be inserted, and this is particularly desirable where the device is used as a dating stamp.

The ink is transferred to the printing roller from the supply roller by means of the inking rollers 27, which are arranged oppositely to engage with both the printing and supply roller. These inking rollers are provided with floating shafts 28 connected by the coiled springs 29, so that the rollers are held yieldingly against the printing and 45 supply rollers, and they accommodate themselves to variations or irregularities therein, such as variations in the type, or variations in the inking pad, and other irregularities. The channels of the side plates accommodate 50 these springs 29.

The rollers are provided with disks 30 at their ends, providing flanges which travel on the printing roller on the inside of their treads, the inking rollers being of such 55 length that the flanges lie at the ends of the supply roller. These flanges perform the double purpose of supporting the inking rollers when they travel over the blank spaces in the type, and also guarding the 60 treads so that they do not become covered with ink, in which case they would mark the surface receiving the imprint.

The rollers arranged in pairs transfer the 65 ink to the printing roller when it is rotated in either direction, so that in use it is kept

properly supplied with ink. This arrangement of parts permits the structure to be made very compact, and, at the same time, the supply and printing rollers may be of substantial dimensions. The supply roller is 70 rotated in operation so that the ink carried thereby is effectively distributed to the inking rollers and by them to the printing roller. The tension of the springs 29 is such that while the inking rollers are held yieldingly in position, they are not held against the inking roller with such stress as to cause them to take an undue supply of ink. The 75 ink can be supplied, as stated, through the top of the housing by removing the handle 7.

The casing, as thus formed, is dust proof, the working parts are protected so that the structure is clean and sanitary, and does not smudge or smear the surface on which 85 it is laid. The parts are quite simple and economical to produce, and are designed so that they may be easily assembled and adjusted in use. The structure is strong and capable of withstanding very severe usage. 90

I have illustrated and described my improvements in an embodiment or adaptation which I find very practical. I have not attempted to illustrate or describe other adaptations or embodiments, as I believe the 95 disclosure made will enable those skilled in the art to which my invention relates to embody the same as may be desired.

Having thus described my invention, what I claim as new and desire to secure 100 by Letters Patent is:

1. In a device of the class described, the combination of a housing comprising removable side plates having opposed spindle supporting bosses surrounded by spring 105 housing barrels, spindles threaded into said bosses and provided with collars, a printing roller mounted on said spindles at the inner sides of their said collars, said roller being recessed at its ends to receive said spring 110 housing barrels, and having alined internal driving lugs, a pair of driving members mounted on said spindles at the outer sides of said collars and provided with driving lugs engaging the said driving lugs of said 115 roller on opposite sides thereof, oppositely acting coiled springs arranged in said barrels with their outer ends connected thereto and their inner ends connected to said driving members so that when the roller is rotated in either direction from its initial position, it is returned to its initial position by one of said springs, said roller being provided with resilient type and with continuous resilient treads at its ends, and means 120 for inking said roller as it is rotated.

2. In a device of the class described, the combination of a housing comprising removable side plates having opposed spindle supporting bosses surrounded by spring 125

housing barrels, spindles threaded into said bosses and provided with collars, a printing roller mounted on said spindles at the inner sides of their said collars, said roller being recessed at its ends to receive said spring housing barrels, and having alined internal driving lugs, a pair of driving members mounted on said spindles at the outer sides of said collars, and provided with driving lugs 5 engaging the said driving lugs of said roller on opposite sides thereof, oppositely acting coiled springs arranged in said barrels with their outer ends connected thereto and their inner ends connected to said driving members so that when the roller is rotated in either direction from its initial position, it is returned to its initial position by one of said springs.

3. In a structure of the class described, 20 the combination of a housing open at the bottom, a printing roller mounted in said housing to project through said opening and having recesses at its ends with alined driving lugs therein, said roller being provided 25 with resilient type and treads, oppositely disposed spindles provided with thrust collars for said roller, a pair of oppositely acting coiled springs connected at their outer ends to said housing, a pair of driving members 30 mounted on said spindles at the outer sides of said collars, the inner ends of said springs being connected to said driving members, said driving members being provided with driving lugs engaging opposite 35 sides of said driving lugs on said roller so that when the roller is rotated in either direction it is returned to its initial position by one of said springs when released, and means for inking said roller as it is rotated.

4. In a structure of the class described, 40 the combination of a housing open at the bottom, a printing roller mounted in said housing to project through said opening and having recesses at its ends with alined driving lugs therein, oppositely disposed spindles 45 provided with thrust collars for said roller, a pair of oppositely acting coiled springs connected at their outer ends to said housing, and a pair of driving members 50 mounted on said spindles at the outer sides of said collars, the inner ends of said springs being connected to said driving members, said driving members being provided with driving lugs engaging opposite sides of said 55 driving lugs on said roller so that when the roller is rotated in either direction it is returned to its initial position by one of said springs when released.

5. In a structure of the class described, 60 the combination of a housing, a printing roller mounted in said housing to rotate in either direction from an initial position and having alined driving lugs, rotatable driving members mounted at the ends of said 65 printing roller and having driving lugs en-

gaging opposite sides of the driving lugs of said printing roller, and oppositely acting springs connected at one end to said housing and at their other ends to said driving members so that when the roller is rotated in either direction from its initial position it is returned to that position by one of said springs when released.

6. In a structure of the class described, 70 the combination of a housing, a printing roller mounted in said housing to rotate in either direction from an initial position and having driving lugs, rotatable driving members having driving lugs engaging opposite sides of the driving lugs of said printing 75 roller, and oppositely acting springs connected at one end to said housing and at their other ends to said driving members so that when the roller is rotated in either direction from its initial position it is returned to that position by one of said springs when released.

7. In a structure of the class described, 80 the combination of a printing roller provided with driving lugs, driving members 85 having driving lugs coacting with opposite sides of said printing roller driving lugs, and oppositely acting springs connected to said driving members so that when the roller is rotated in either direction it is returned to its initial position by one of said springs.

8. In a structure of the class described, 90 the combination of a printing roller rotatable in either direction from an initial position, said roller being provided with an annular resilient tread, means for returning said roller to its initial position when rotated in either direction including oppositely acting springs, said springs being 95 operatively associated with said roller so that one spring is neutral when the other is in action, and means for inking said roller as it is rotated.

9. In a structure of the class described, 100 the combination of a printing roller rotatable in either direction from an initial position, means for returning said roller to its initial position when rotated in either direction including oppositely acting springs, 105 said springs being operatively associated with said roller so that one spring is neutral when the other is in action, and means for inking said roller as it is rotated.

10. In a structure of the class described, 110 the combination of a housing, a printing roller mounted in said housing to rotate in either direction from an initial position and having alined driving lugs, said roller being provided with resilient type and resilient 115 annular treads at its ends, rotatable driving members mounted at the ends of said printing roller and having driving lugs engaging opposite sides of the driving lugs of said printing roller, oppositely acting coiled 120

- 5 springs connected at one end to said housing and at their other ends to said driving members so that when the roller is rotated in either direction from its initial position it is returned to that position by one of said 10 springs, an ink supply roller mounted in a spaced relation to said printing roller, a pair of inking rollers disposed oppositely between said inking and supply rollers to 15 coat with both, said inking rollers being provided with floating spindles and with disks traveling on said printing roller at the inside of its said treads and at the ends of said supply roller, and springs connecting the ends of said floating spindles whereby the inking rollers are held yieldingly against the supply and printing rollers.
- 10 11. In a structure of the class described, the combination of a housing, a printing roller mounted in said housing to rotate in either direction from an initial position and having alined driving lugs, rotatable driving members mounted at the ends of said printing roller and having driving lugs engaging opposite sides of the driving lugs of said printing roller, oppositely acting springs connected at one end to said housing and at their other ends to said driving members so that when the 15 roller is rotated in either direction from its initial position it is returned to that position by one of said springs, an ink supply roller mounted in a spaced relation to said printing roller, a pair of inking rollers disposed oppositely between said inking and supply rollers to 20 coat with both, said inking rollers being provided with floating spindles and with disks traveling on said printing roller at the inside of its said treads and at the ends of said supply roller, and springs connecting the ends of said floating spindles whereby the inking rollers are held yieldingly against the supply and printing rollers.
- 25 12. In a structure of the class described, the combination of a printing roller rotatable in either direction from its initial position, means for stopping said roller at its initial position, spring means for returning said roller to its initial position when it is rotated in either direction therefrom, an ink supply roller disposed in a spaced relation to said printing roller, a pair of inking rollers disposed oppositely between said supply and printing rollers and coacting with both, floating spindles for said rollers, and springs connecting the ends of said spindles so that the inking rollers are held yieldingly against the supply and printing 30 rollers.
- 35 13. In a structure of the class described, the combination of a printing roller rotatable in either direction from its initial position, means for stopping said roller at its initial position, spring means for returning said roller to its initial position when it is rotated in either direction therefrom, an ink supply roller disposed in a spaced relation to said printing roller, a pair of inking rollers disposed oppositely between said supply and printing rollers and coacting with both, floating spindles for said rollers, and springs connecting the ends of said spindles so that the inking rollers are held yieldingly against the supply and printing 35 rollers.
- 40 14. In a structure of the class described, the combination of a printing roller provided with resilient type and resilient treads at its ends, an ink supply roller mounted in said housing in a spaced relation to said printing roller, a pair of inking rollers disposed oppositely between said printing and supply rollers coacting with both, said inking rollers being provided with floating spindles, and springs connecting the ends of said inking roller spindles whereby they are yieldingly held against the supply and printing rollers, said inking rollers being provided with flanges at their ends traveling on the printing roller within its said treads.
- 45 15. In a structure of the class described, the combination of a printing roller adapted to rotate in either direction from an initial position, said roller being provided with annular treads disposed at the outside of the type carried thereby, means for automatically returning said roller to its initial position, an ink supply roller mounted in a spaced relation to said printing roller, a pair of floating inking rollers disposed between said inking and supply rollers to coact with both, said inking rollers being provided with flanges traveling on said printing roller on the inside of its said treads, and springs connecting said rollers whereby they are held yieldingly against the supply and printing rollers.
- 50 16. In a structure of the class described, the combination of a printing roller adapted to rotate in either direction from an initial position, means for automatically returning said roller to its initial position, an ink supply roller mounted in a spaced relation to said printing roller, a pair of floating inking rollers disposed between said inking and supply rollers to coact with both, and springs connecting said rollers whereby they are held yieldingly against the supply and printing rollers.
- 55 17. In a structure of the class described, the combination of a printing roller provided with annular resilient treads at its ends, an ink supply roller mounted in spaced relation to said printing roller, a pair of inking rollers disposed oppositely between said printing and supply rollers coacting with both, and means for yieldably supporting said inking rollers against the supply and printing rollers, said inking rollers being provided with flanges traveling on the printing roller within its said treads.
- 60 18. In a structure of the class described, the combination of a printing roller provided with annular resilient treads at its ends, an ink supply roller mounted in spaced relation to said printing roller, a pair of inking rollers disposed oppositely between said printing and supply rollers coacting with both, and means for yieldably supporting said inking rollers against the supply and printing rollers, said inking rollers being provided with flanges traveling on the printing roller within its said treads.
- 65 19. In a structure of the class described, the combination of a printing roller provided with annular resilient treads at its ends, an ink supply roller mounted in spaced relation to said printing roller, a pair of inking rollers disposed oppositely between said printing and supply rollers coacting with both, and means for yieldably supporting said inking rollers against the supply and printing rollers, said inking rollers being provided with flanges traveling on the printing roller within its said treads.

70 75 80 85 90 95 100 105 110 115 120 125 130

ing said roller to its initial position when it is rotated in either direction therefrom an ink supply roller disposed in a spaced relation to said printing roller, a pair of floating inking rollers disposed between and on opposite sides of said supply and printing rollers to coact with both, and a resilient connection for said roller.

14. In a structure of the class described, the combination of a printing roller provided with resilient type and resilient treads at its ends, an ink supply roller mounted in said housing in a spaced relation to said printing roller, a pair of inking rollers disposed oppositely between said printing and supply rollers coacting with both, said inking rollers being provided with floating spindles, and springs connecting the ends of said inking roller spindles whereby they are yieldingly held against the supply and printing rollers, said inking rollers being provided with flanges at their ends traveling on the printing roller within its said treads.

15. In a structure of the class described, the combination of a printing roller adapted to rotate in either direction from an initial position, said roller being provided with annular treads disposed at the outside of the type carried thereby, means for automatically returning said roller to its initial position, an ink supply roller mounted in a spaced relation to said printing roller, a pair of floating inking rollers disposed between said inking and supply rollers to coact with both, said inking rollers being provided with flanges traveling on said printing roller on the inside of its said treads, and springs connecting said rollers whereby they are held yieldingly against the supply and printing rollers.

16. In a structure of the class described, the combination of a printing roller adapted to rotate in either direction from an initial position, means for automatically returning said roller to its initial position, an ink supply roller mounted in a spaced relation to said printing roller, a pair of floating inking rollers disposed between said inking and supply rollers to coact with both, and springs connecting said rollers whereby they are held yieldingly against the supply and printing rollers.

17. In a structure of the class described, the combination of a printing roller provided with annular resilient treads at its ends, an ink supply roller mounted in spaced relation to said printing roller, a pair of inking rollers disposed oppositely between said printing and supply rollers coacting with both, and means for yieldably supporting said inking rollers against the supply and printing rollers, said inking rollers being provided with flanges traveling on the printing roller within its said treads.

18. In a structure of the class described, the combination of a printing roller, said roller being provided with annular treads disposed at the outside of the type carried thereby, an ink supply roller mounted in a spaced relation to said printing roller, and a pair of inking rollers disposed between said inking and supply rollers coacting with both, said inking rollers being provided with flanges traveling on said printing roller at the inside of its said treads. 40
19. In a structure of the class described, the combination of a printing roller provided with annular resilient treads, the treads being disposed at the outside of the type on the roller, an ink supply roller mounted in spaced relation to said printing roller, and an inking roller held yieldingly against said printing and supply rollers and provided with flanges traveling on said printing roller between its said treads and type whereby the treads are protected from the ink, and the inking roller is supported while passing blank spaces in the printing roller. 45
20. In a structure of the class described, the combination of a printing roller provided with resilient type and with resilient annular treads formed integrally therewith, the treads being disposed at the outside of the type, a supply roller mounted in spaced relation to said printing roller, and a floating inking roller held yieldingly against said printing and supply rollers and provided with flanges traveling on said printing roller on the inside of its said treads whereby the treads are protected from the ink. 50
21. In a structure of the class described, the combination of a printing roller provided with annular resilient treads, a supply roller mounted in spaced relation to said printing roller, and a floating inking roller held yieldingly against said printing and supply roller and provided with flanges traveling on said printing roller on the inside of its said treads whereby the treads are protected from the ink. 55
22. In a structure of the class described, the combination of a housing open at the bottom and comprising removable side plates having opposed supply roller shaft bosses at their upper ends and opposed printing roller spindle bosses at their lower ends, and offsets providing integral horizontal channels intermediate of said pairs of bosses, a supply roller shaft carried by said upper bosses and printing roller spindles carried by said lower bosses, a supply roller mounted on said shaft, a printing roller mounted on said spindles for rotating in either direction from its initial position, springs for returning said roller to its initial position, a pair of inking rollers disposed oppositely between said supply and printing rollers and provided with shafts projecting into said channels, and coiled springs connecting the ends of said shafts disposed in said channels. 60
